UNITED STATES PATENT OFFICE.

GIULIO MARCHETTI, OF HALIFAX, ENGLAND.

DESIGN FOR CARPET.

SPECIFICATION forming part of Design No. 23,438, dated July 10, 1894.

Application filed April 17, 1894. Serial No. 507,924. Term of patent 3½ years.

To all whom it may concern:

Be it known that I, GIULIO MARCHETTI, a subject of the Queen of Great Britain, and a resident of Halifax, in the Kingdom of England, have invented a certain new and original Design for Carpets and Borders, of which the following is a specification.

The accompanying drawing is a face view of a portion of a carpet and border embodying my invention.

The body A is characterized by a series of large sprays of flower and leaf forms openly distributed and smaller interspersed sprays of flower and leaf forms. The smaller sprays are caught up by wavy bands, from which slender leaf-like forms spread in wavy lines about the larger sprays.

The border is characterized by large sprays of flower and leaf forms with a serrated wavy border on the inner edge and on the outer

edge a border of general wavy appearance having sprays of flower forms caught up by flowing bands and joined together by rows of wavy slender leaf forms.

What I claim as my design, and desire to secure by Letters Patent, is—

1. In a design for a carpet, the body substantially as shown and described.

2. In a design for a carpet, the border substantially as shown and described.

3. The design for a carpet, comprising the body A and border B substantially as shown and described.

In testimony whereof I have signed my name to this specification in the presence of two subscribing witnesses.

GIULIO MARCHETTI.
